FOLDING SWING

William J. Foley, Bayonne, N. J.

Application September 20, 1933, Serial No. 690,204

10 Claims. (Cl. 155—68)

This invention relates to a folding swing.

The object of the invention is the production of a swing which can be easily folded when not in use.

5 The second object of the invention is the production of a swing, which the user thereof can easily start swinging, maintain the swinging of the swing and stop the same without assistance.

10 The third object of the invention is the production of a folding swing which can be detachably secured to a support.

15 The fourth object of the invention is the production of a swing, which can be detachably supported from the head of a door frame and the like.

20 In the accompanying drawings, Fig. 1 represents a rear view partly broken away of an exemplification of the folding swing; Fig. 2 shows a section of Fig. 1 on the line 2, 2; Fig. 3 indicates a section of Fig. 1 as on the line 2, 2 with the swing in its folded position; Fig. 4 represents a section of Fig. 2 on the line 4, 4; Fig. 5 shows a second of the line 5, 5 of Fig. 2; Fig. 6 is a section on the line 6, 6 of Fig. 2; Fig. 7 represents a bottom view of some details of the swing and Fig. 25 8 is a section on the line 8, 8 of Fig. 7.

30 The improved folding swing is shown to comprise, in this instance, the pair of front suspension bars 20, and the pair of rear suspension bars 21.

35 Each of the bars 21 is indicated with the elongated upper guide opening 22, and the elongated lower guide opening 23.

40 At the upper end of each of the suspension bars 20 and 21 is indicated an eyelet comprising the longitudinal members 26, which have integral therewith the hook ends 27. The members 26 at their upper ends are connected by the cross members 28, which are substantially elongated in depth as indicated. Screw pivots 30 extend through the upper ends of the suspension bars 20 and 21, and the hook ends 27 engage said screw pivots. Upper cross bars 32 connect the suspension bars 20 and 21 and lower cross bars 33 connect the suspension bars 21.

45 Normally horizontal arms 35 have the bifurcated outer ends 36, and from their other ends extend the pivots 37, which latter engage the elongated openings 22.

50 Normally inclined supporting arms 40, at their lower ends are pivoted to the suspension bars 21, by means of the pivots 41, and at their upper ends have integral therewith the tenons 42, which are seated in the bifurcated ends 36.

55 A cross bar 45 has extending from its ends the pivots 46, which extend through the bifurcated

ends 36 and the tenons 42. The rear edges of the inclined supporting arms 40 are connected by the upper supporting cross brace 47 and the lower supporting cross brace 48.

To the cross bar 45 is fastened the normally inclined seat back designated in its entirety by the numeral 50. The seat back 50 comprises the normally longitudinal inclined members 54 which are fastened to the cross bar 45. Cross braces 55 and 56 are connected to the members 54 at their rear faces and the lower supporting brace 57 is connected to the front faces of the lower ends of the inclined members 54.

A seat 60 is indicated with its thickened front end 61 and the rear rabbet end 62. Pivot 15 screws 65 project from the sides of the seat 60, and extend through the lower guide openings 23 of the suspension bars 21. Wing nuts 66 engage the pivot screws 65 to maintain the seat 60 in place. The rabbet end 62 of the seat 60 is adapted to bear on the supporting brace 57 or on the lower supporting cross brace 48. The seat 60 can be lowered from the position shown in the drawings, see Fig. 2, by unscrewing the wing nuts 66, and lowering the said seat, and in which case the pivot screws 65 will be lowered in the guide openings 23 and the rabbet end 62 will be brought to bear on the lower supporting cross brace 48.

An operating frame is designated in its entirety by the numeral 70. The frame 70 comprises a pair of arms 71 which are supported on the pivot bolt 72, and the end portions of the latter extend through openings in the suspension bars 20 to pivotably support the handle frame 70.

An operating handle bar 75 extends between and is fastened to the arms 71. A cross brace 76 connects the outer edges of the suspension bars 20 and the adjacent and outer ends of the arms 71 normally bear up against the cross brace 76.

The lower ends of the suspension bars 20 and 21 have extending therethrough the pivot cross bolts 78 having the nuts 79 in threaded engagement therewith. A foot platform is designated in its entirety by the numeral 80. The foot platform 80 comprises the supporting bars 84 which have their ends supported on the bolts 78. Foot plates 85 are supported upon and fastened to the supporting bars 84.

The upper member of a door frame or swing 50 support is indicated by the numeral 86 with its door stop 87, its lower face 88 and side faces 89. Hooks 90 extend from the side faces 89. U shaped metallic supporting brackets 91 are fastened to the member 86 at its lower face 88. Each of the 55

supporting brackets 91 comprises the plate 92, from which extend the feet 93 that are fastened to the member 86, by means of screws 94. In each of the plates 92 is indicated an elongated opening 96, which joins with a circular opening 97.

A suspension frame is designated in its entirety by the numeral 100.

The suspension frame 100 comprises the longitudinal members 102. Supporting hooks 103 extend from the members 102. A central cross member 105 having the recesses 106, the outer cross members 108 and the stop cross member 110 are fastened to the longitudinal member 102. Inclined openings 114 are indicated in the outer cross members 108 and bolts 115, having the eyelets 116 and the nuts 117 extend through the inclined openings 114. Rings 118 extend through the eyelets 116. Clamping bolts 120 are indicated with the recesses 121 and the heads 122, which latter are smaller in diameter than the circular openings 97 of the plates 92. The bolts 120 extend through the central cross member 105 and the openings of the plates 92. A wing nut 124 is provided for each of the bolts 120.

To locate the suspension frame 100 in operative position, the recesses 106 of the cross member 105 are brought to bear against the lower faces of the plates 92, and the cross member 110 is brought to bear against one of the side faces 89 of the member 86. The rings 118 are engaged with the hooks 90. The bolts 120 are connected to the plates 92 by first extending their heads 122 through the circular openings 97 and are then moved to engage the recesses 121 in the openings 96. The operator then tightens the nuts 117 on the bolts 115 and the wing nuts 124 on the bolts 120 are tightened in place to tightly secure the suspension frame 100 in operative position. The recesses 121 coacting with the sides of the openings 96 prevent the bolts 120 turning.

To disconnect the swing from the supporting hooks 103, the eyelets having the longitudinal members 26 are disconnected from said supporting hooks. The depths of the cross members 28 of the eyelets prevent the accidental disengagement of said eyelets from the supporting hook 103.

To disengage the suspension frame 100 from the member 86 of the door frame, the wing nuts 124 are slightly unscrewed from the clamping bolts 120 and said bolts are moved in the elongated openings 96 of the plate 92 until the heads 122 are in line with the circular openings 97. The nuts 117 are slightly unscrewed, the rings 118 are disengaged from the hooks 90 and the suspension frame 100 can then be lowered from the member 86.

The user of the swing is seated on the seat 60 with his feet bearing on the foot plates 85, and to start the swing bears on the operating handle bar 75, which will tilt the foot platform 80 with its foot plates 85 and start the swing to swing. The user intermittently repeats bearing on the handle bar 75 to keep the swing swinging. To stop the swing, the user grasps the handle bar 75. If desired the seat 60 can be lowered from the position indicated plainly in Fig. 2, by slightly unscrewing the wing nuts 66 of the screws 65, and engaging the rabbet end 62 with the upper edge of the lower supporting cross brace 48.

It will be noted that when the swing is disconnected from the suspension frame 100, the said swing can be folded as indicated in Fig. 3. To fold the swing the pivots 37 are caused to slide up the guide openings 22 and the horizontal arms

35 will swing on the pivots 46, also the inclined supporting arms 40 will swing on the pivots 41. At the same time the suspension bars 21 will swing on their pivot cross bolts 78 and the supporting bars 84 will swing on their pivot bolts 78. 5

Various modifications may be made in the invention and the present exemplification is to be taken as illustrative and not limitative thereof.

Having described my invention, I claim:

1. In a swing the combination of a pair of front 10 suspension bars and a pair of rear suspension bars, means to swingingly support the upper ends of the suspension bars, a foot platform pivotally connected to the lower ends of the suspension bars, a cross brace connecting the outer edges of 15 the pair of front suspension bars, an operating frame comprising a pair of arms, said arms pivotally connected to the pair of front suspension bars, an operating handle connecting said arms, the outer ends of the arms of the operating frame 20 normally bearing up against said cross brace and a seat detachably connected to the pair of rear suspension bars adapted to be secured to said rear suspension bars at various levels, the user of the swing when bearing on said operating handle 25 tilting the foot platform and swinging the swing.

2. In a swing the combination of a pair of front suspension bars and a pair of rear suspension bars, said rear suspension bars each having an elongated upper guide opening and a lower elongated 30 guide opening, a foot platform in pivotal connection with the lower ends of the suspension bars, a normally inclined supporting arm in pivotal connection with the lower portion of each of said rear suspension bars, an upper supporting 35 cross brace connecting the rear edges of said normally inclined supporting arms, a pair of normally horizontal arms, each having its front end in pivotal engagement with one of the elongated guide openings of said rear suspension bars, a 40 seat back in pivotal engagement with the rear ends of said normally horizontal arms and the upper ends of said normally inclined supporting arms, a lower supporting brace connected to the seat back at its front face and a seat having its 45 front end in pivotal connection with the lower elongated openings of said rear suspension bars, the rear end of said seat adapted to bear on the lower supporting brace of said seat back and said seat back adapted to bear on the upper 50 supporting brace of said inclined supporting arms.

3. In a swing the combination of a pair of front suspension bars and a pair of rear suspension bars, the latter having each an elongated opening, means to connect the lower ends 55 of the suspension bars, inclined supporting arms connected to the rear suspension bars, an upper and a lower supporting cross brace connecting said inclined arms, a seat back in connection with said inclined arms, a supporting brace connected to the seat back at its front face and a seat having its front end in detachable connection with the upper ends of the elongated openings of said rear suspension bars, with its rear end adapted to bear on the supporting brace 60 of said seat back, and the front end of said seat adapted to be supported in the lower ends of the openings of said rear suspension bars and the rear end of said seat also adapted to bear on the lower supporting cross brace of said inclined arms. 65

4. In a swing the combination of a pair of front suspension bars and a pair of rear suspension bars, the latter each having an elongated guide opening, a foot platform connected to the 70

lower ends of the suspension bars, inclined supporting arms, means to connect the inclined arms to said rear suspension bars, an upper and a lower supporting cross brace connecting the rear edges of said inclined arms, a seat back in pivotal connection with said inclined arms, a supporting brace connected to the seat back at its front face, and a seat having its front end in detachable pivotal connection with the upper ends of the elongated openings of said rear suspension bars with the rear end adapted to bear on the supporting brace of the seat back, and the front end of said seat adapted to be pivotally supported in the lower ends of the openings of said rear suspension bars, and the rear end of said seat also adapted to bear on the lower supporting cross brace of said inclined arms.

5. In a swing the combination of a pair of front suspension bars and a pair of rear suspension bars, the latter having each an upper elongated guide opening and a lower elongated guide opening, a foot platform connected to the lower ends of the suspension bars, a normally inclined supporting arm connected to the lower portion of each rear suspension bar, an upper supporting cross brace connecting the rear edges of said inclined supporting arms, a pair of normally horizontal arms, each having its front end in pivotal engagement with one of the elongated upper guide openings in said rear suspension arms, a cross bar having its ends in pivotal connection with said normally horizontal arms and the upper ends of said inclined supporting arms, a seat back fastened to said cross brace, a supporting brace connected to the seat back at its front face and a seat having its front end in detachable pivotal connection with the lower elongated openings of said rear suspension bars and the rear end of said seat adapted to bear on the supporting brace of said seat back, and said seat back adapted to bear on the upper supporting brace of the inclined supporting arms.

6. In a swing the combination of a pair of front suspension bars and a pair of rear suspension bars, said rear suspension bars having each an elongated upper guide opening and an elongated lower guide opening, an operating frame in pivotal connection with said front suspension bars, a foot platform in pivotal connection with the lower ends of the suspension bars, a normally inclined supporting arm in pivotal connection with the lower portion of each of said rear suspension bars, an upper supporting cross brace connecting the rear edges of said normally inclined supporting arms, a pair of normally horizontal arms, each having its front end in pivotal engagement with one of the elongated upper guide openings of said rear suspension bars, a cross bar having its ends in pivotal connection with the rear ends of said normally horizontal arms and the upper ends of said normally inclined supporting arms, a seat back comprising a plurality of normally longitudinal inclined

members, cross braces connecting the rear faces of said members, a supporting brace connecting the front faces of said members at their lower portions, and a seat having its front end in pivotal connection with the elongated lower openings of said rear suspension bars, and the rear end of said seat adapted to bear on the supporting brace connecting the front faces of the members of the seat back, said members of the seat back adapted to bear on the upper supporting brace of the inclined supporting arms.

7. In combination a swing, a suspension frame, means to swingingly connect the swing to said suspension frame, said suspension frame comprising a pair of longitudinal members, a pair of outer cross members connecting the longitudinal members of the suspension frame, a central cross brace connecting the said longitudinal members of the suspension frame, a swing support, a pair of U shaped supporting brackets depending from the swing support and means to detachably connect said central cross brace to said U shaped supporting brackets.

8. In combination, a swing, a suspension frame, means to swingingly connect the swing to said suspension frame, said frame comprising a pair of longitudinal members, a pair of outer cross members and a central cross brace connected to the said longitudinal members of the suspension frame at the upper faces of said longitudinal members, a swing support, a pair of U shaped supporting brackets depending from the swing support, means to detachably connect said central cross brace to said U shaped supporting brackets and means to detachably connect said outer cross members to said swing support.

9. In a swing the combination of means for suspending said swing from the header of a door frame or other support in which the header bar is provided with a depending stop member, said means including a suspension frame and means to swingingly connect the swing to said suspension frame, said frame comprising a pair of longitudinal members, a central cross member and lateral cross members parallel to and spaced from said central cross member, and means for detachably connecting said central cross member to the header bar with one of the lateral cross members bearing against a side face of said stop member.

10. In a swing the combination of a pair of front suspension bars and a pair of rear suspension bars, means to swingingly support the upper ends of said suspension bars, a foot platform pivotally connected to the lower ends of the suspension bars, a cross brace connected to the pair of front suspension bars, and a handle frame pivotally connected to the pair of front suspension bars adjacent to and below said cross brace, for the operator of the swing to bear upon and thereby tilt the said foot platform to an inclined position to swing the swing.

WILLIAM J. FOLEY.
